(74) *Attorney, Agent, or Firm* — Ralph E. Smith

(57) **CLAIM**

The ornamental design for a running board, as shown and described.

DESCRIPTION

FIG. 1 is a front perspective view of a running board showing our new design;

FIG. 2 is a rear perspective view thereof;

FIG. 3 is a right side view thereof;

FIG. 4 is a left side view thereof;

FIG. 5 is a front view thereof;

FIG. 6 is a rear view thereof;

FIG. 7 is a top plan view; and,

FIG. 8 is a bottom view.

It will be understood that the broken lines shown in the drawings illustrate portions of the running board that form no part of claimed design.

1 Claim, 5 Drawing Sheets
